UNITED STATES PATENT OFFICE.

FRANCIS J. COLE, OF NEW YORK, AND CARL J. MELLIN, OF SCHENECTADY, NEW YORK, ASSIGNORS TO AMERICAN LOCOMOTIVE COMPANY, OF NEW YORK, N. Y., A CORPORATION OF NEW YORK.

SUPERHEATER.

No. 830,822.

Specification of Letters Patent.

Patented Sept. 11, 1906.

Application filed March 28, 1906. Serial No. 307,985.

To all whom it may concern:

Be it known that we, FRANCIS J. COLE, of the borough of Manhattan, in the city of New York, and CARL J. MELLIN, of Schenectady, in the county of Schenectady, State of New York, have invented a certain new and useful Improvement in Steam-Boiler Superheaters, of which improvement the following is a specification.

Our invention relates to superheaters of the general class or type in which the superheater-pipes are located in fire-tubes of a steam-boiler; and its object is to provide means for connecting the rear ends of the superheater-pipes, which will facilitate the cleaning of the pipes and superheating-tubes and measurably prevent the accumulation of hard deposit on the ends of the former.

The improvement claimed is hereinafter fully set forth.

In the accompanying drawings, Figure 1 is a longitudinal central section through a portion of one of the superheating-tubes of a locomotive-boiler and through a portion of a header to which the superheater-pipes are connected; Fig. 2, a transverse section on the line *a a* of Fig. 1; Fig. 3, a vertical longitudinal central section, on an enlarged scale, through one of the return-bends; and Fig. 4, a rear view in elevation of the same.

Our invention is herein exemplified as applied in a superheater of the character of that set forth in Letters Patent of the United States No. 782,490, granted and issued to the American Locomotive Company, as our assignee, under date of February 14, 1905, there being, as in the construction of said Letters Patent, a plurality of superheater-pipes 69, extending longitudinally in pairs or in *U* form, in each of a set of superheating-tubes 67, which are of larger diameter than the ordinary fire-tubes of the boiler. The superheater-pipes which form steam-channels directly exposed throughout their length to the heat of the superheating-tubes, are connected at their forward ends to headers 70 of suitable construction which are located in advance of the front flue-sheet or flue-head 4^d and which as they do not form part of our present invention need not be herein at length described. The rear ends of the superheater-pipes of each pair or *U* are connected by return-bends, those, 69^d, of the up-

per pairs of pipes in the superheater-tubes, which are located in advance of those of the lower pairs of the several tubes, being flattened or substantially semi-elliptical in longitudinal section, as shown in Fig. 1.

The rear ends of the lower pairs of superheater-pipes are connected by transversely curved or segmental return-bends 69^c, having threaded nozzles 69^b, projecting from the lower ends of their front sides for the attachment of the superheater-pipes 69. The bodies of the return-bends 69^c are flattened on their lower sides at and adjacent to their front ends and are upwardly tapered or inclined for the remainder of their length to a narrow edge at their rear ends, their lower surfaces being thereby made substantially semiconical or half-funnel shaped, as clearly indicated in Figs. 3 and 4. Lateral feet or projections 69^b, the faces of which are curved correspondingly with the inner surfaces of the superheating-tubes 67, are formed on the lower portions of the return-bends 69^c, said feet or projections abutting against the inner surfaces of the superheating-tubes and supporting and firmly holding the rear ends of the superheater-pipes at a desired and determined level therein.

By the employment of return-bends of the construction above described for the connection of the rear ends of superheater-pipes we attain the substantial advantages in practice of reducing the resistance to the passage of the products of combustion through the superheating-tubes, facilitating the cleaning of said tubes and the superheater-pipes, and considerably reducing the formation of a hard deposit upon the return-bends and pipes, which has been found to occur in the use of connections of the ordinary construction.

We claim as our invention and desire to secure by Letters Patent—

1. In a steam-boiler superheater, a segmental return-bend connection for the rear ends of superheater-pipes which is upwardly and rearwardly tapered or inclined on its lower side, so as to present thereon a substantially semiconical or half-funnel face to products of combustion passing around it.

2. In a steam-boiler superheater, a return-bend connection for the rear ends of superheater-pipes, which is of transversely-curved or segmental form, provided with longitudinal

nozzles on its front for the attachment of superheater-pipes, and upwardly and rearwardly tapered or inclined on its lower side, so as to present thereon a substantially semi-conical or half-funnel surface.

3. In a steam-boiler superheater, a return-bend connection for the rear ends of superheater-pipes, which is of transversely-curved or segmental form, provided with longitudinal nozzles on its front for the attachment of superheater-pipes, upwardly and rearwardly tapered or inclined on its lower side, and provided with lateral feet or projections curved to abut against a superheating-tube.

4. In a steam-boiler superheater, the combination of a superheating-tube, two superheater-pipes extending longitudinally therein, and a transversely-curved or segmental return-bend attached to the rear ends of the superheater-pipes and having its lower side upwardly and rearwardly tapered or inclined so as to present thereon a substantially semi-

conical or half-funnel face to products of combustion passing through the superheating-tube.

5. In a steam-boiler superheater, the combination of a superheating-tube, two superheater-pipes extending longitudinally therein, and a transversely-curved or segmental return-bend attached to the rear ends of the superheater-pipes and having its lower side upwardly and rearwardly tapered or inclined and provided with lateral feet or projections abutting against the inner surface of the superheating-tube.
